CLAIM

The ornamental design for a fountain brush, as shown
and described.

DESCRIPTION

FIG. 1 is a perspective view of a fountain brush, showing
our new design;

FIG. 2 is a front elevational view thereof;

FIG. 3 is a side elevational view thereof;

FIG. 4 is a rear elevational view thereof;

FIG. 5 is a bottom plan view thereof;

FIG. 6 is a top plan view thereof, shown in the trans-
verse position;

FIG. 7 is a top plan view thereof, shown with the brush
head in the lengthwise position.

FIG. 1

FIG. 2

FIG. 3

FIG. 4

FIG. 5
